(57) **CLAIM**

The ornamental design for a firemen extendable ramming pole with a pike head, as shown and described.

DESCRIPTION

FIG. 1 is a perspective view of the firemen extendable ramming pole with a pike head of the instant invention;

FIG. 2 is a front elevation view thereof, wherein the rear elevation view is a mirror image;

FIG. 3 is a top plane view thereof;

FIG. 4 is a bottom plane view thereof;

FIG. 5 is an elevation view taken from the left end of FIG. 2; and,

FIG. 6 is an elevation view taken from the right end of FIG. 2.
